DESIGN FOR AN ADVERTISING DISPLAY STAND

Sydney G. Silberstein, Brooklyn, N. Y.

Application April 25, 1941, Serial No. 100,618

Term of patent 7 years

To all whom it may concern:

Be it known that I, Sydney G. Silberstein, a citizen of the United States, residing at Brooklyn, in the county of Kings and State of New York, have invented a new, original, and ornamental Design for Advertising Display Stand, of which the following is a specification, reference being had to the accompanying drawing, forming a part thereof.

I claim:

The ornamental design for an advertising display stand, as shown.

SYDNEY G. SILBERSTEIN.
